INTERLOCKING FILING CASE

Hans W. Regenhardt, Cleveland, Ohio, assignor
to Record Files, Inc., Wooster, Ohio, a corpora-
tion of Ohio

Application October 15, 1946, Serial No. 703,293

13 Claims. (Cl. 312—111)

1

This invention relates to filing cabinets and the like, and more particularly to individual filing drawers, cases, compartments or the like provided with means whereby a plurality of such units can be interlocked securely to form a stack.

A general object of the present invention is the provision of individual filing cases, drawers, compartments or the like provided with means whereby two or more such units can be locked securely together without requiring any nuts, bolts, keys or other separately formed locking members. Another object is the provision of interlocking filing units in which adjacent units are securely locked against longitudinal and vertical displacement with respect to each other. Another object is the provision of such units which can be manufactured at relatively low cost. A further object is the provision of such units which can be readily interlocked to form a secure and stable stack and which can also be disassembled readily. Another object is the provision of such units in which the interlocking parts are formed integrally with the shells of the units, requiring no additional material.

Further objects and advantages of my invention will become apparent from the following description of a preferred form thereof, reference being made to the accompanying drawings in which Figure 1 is a perspective view with parts broken away showing two of my units assembled together; Figure 2 is a perspective view of one of the units of Figure 1; Figure 3 is a plan view of the bottom of one of my units; Figure 4 is a section taken along the line 4—4 of Figure 3; Figure 5 is a plan view of the top of one of my units showing the parts which are adapted to interlock with the parts shown in Figure 4; Figure 6 is a section taken along the line 6—6 of Figure 5; Figure 7 is a view on an enlarged scale looking down on the bottom wall of the upper of two interlocked units; and Figure 8 is a section taken along the line 8—8 of Figure 7.

Briefly, units made according to a preferred form of my invention include parts formed on the top and bottom of each unit arranged to interlock with the bottom or top, respectively, of an adjacent unit. The interlocking parts are disposed adjacent the front and rear portions of the units and include oppositely facing interlocking parts arranged so that when two units are assembled together they cannot be moved longitudinally with respect to each other in either direction, nor can either end of the upper unit be displaced vertically with respect to the lower unit. This result is preferably accomplished

5 by oppositely facing interlocking recesses and tongues which are arranged so that the tongue adjacent the rear, for example, of one unit may be engaged within a recess adjacent the rear of another unit with the longitudinal axes of the units angularly displaced, and then the units may be interlocked by rotating one unit with respect to the other about the pivot established by the interengaging tongue and recess to bring the longitudinal axes of the units into substantial alignment and thereby bring the interlocking parts adjacent the front ends of the units into locking engagement with each other. In other words, the locking engagement at one end of the 10 units is made by relative movement between the units in a generally longitudinal direction, and the locking engagement at the other end is made by lateral movement, by swinging one unit with respect to the other to bring their axes into substantial alignment.

15 As shown particularly in Figures 1 and 2, each unit made according to my invention preferably comprises a steel shell having a top wall 10, side walls 11 and a bottom wall 12. The shell is 20 preferably reinforced by a front steel reinforcement 13 and the back of the shell is closed by a flanged member 14. The flanges 15 (see Figure 8) of the back 14 may be secured to the shell as by spot welding, and the reinforcement 13 may be secured in a similar manner. A drawer 17, which 25 may be of conventional construction, is arranged to fit within the shell, the drawer sliding on the reinforcement 13 and drawer stops 18; the drawer stops 18 and the back 19 of the drawer function 30 to prevent accidental removal of the drawer from the shell. Obviously, other drawer or compartment arrangements may be employed without effecting the interlocking of the units.

35 In order to interlock the units into a secure and stable stack such as shown in Figure 1, each shell is provided with interlocking parts on both the top and bottom thereof. Each top 10 has a raised portion 21 near the rear thereof formed by displacing some of the metal of the shell upwardly as shown, thereby providing a forwardly facing recess 23. Near the front of each shell there is a rearwardly facing locking member 22, the member 22 projecting a slight distance above the plane of the top 10. The bottom 12 of each shell is provided with parts adapted to interfit with the parts 21 and 22 of an adjacent shell. These parts comprise a rearwardly facing tongue 25 at the rear thereof and a recess 26 and forwardly facing tongue 27 at the front end thereof. These parts may be interengaged with the parts

40

45

50

55

21 and 22 as shown in Figure 1 of the drawings, with the tongue 25 disposed within the recess 23 beneath the raised portion 21 and the rearwardly facing locking member 22 engaged by the tongue 27. The configuration of the interengaging parts will be described in greater detail below with reference to the remaining figures of the drawings. However, as shown in Figure 1 the parts interlock to provide an assembly in which longitudinal movement of one unit with respect to the other is impossible, and in which both ends of the upper unit are locked against vertical movement with respect to the lower unit, these desirable results being accomplished without requiring any separately formed locking members, keys, nuts, bolts or the like.

The construction of the interlocking parts and the interlocking engagement between two adjacent units are shown in Figures 3 to 8 of the drawings. Considering first the interlock at the rear of the shells, as shown in Figures 5 and 6 a slot 29 is cut in the top 10 and the metal of the top in back of the slot is displaced upwardly to provide the raised portion 21, leaving the opening 23. As shown in Figures 3 and 4, the tongue 25 is provided by cutting a slot 31 in the metal of the bottom 12 and displacing the metal in back of the slot upwardly to form a bulged portion 32, thereby providing clearance for the raised portion 21 when the units are assembled. As shown in Figures 7 and 8, these parts may be assembled by disposing the upper unit on the lower unit with the raised portion 32 over the raised portion 21, and then sliding the tongue 25 longitudinally into the opening 23 so that it is disposed beneath the raised portion 21. When so assembled, the interengagement between the tongue 25 and the underside of the portion 21 prevents the upper unit from being raised with respect to the lower unit while the engagement of the shoulders 34 adjacent the tongue 25 with the edge portions 35 of the raised portion 21 prevents movement of the upper unit rearwardly with respect to the lower unit. However, one unit may be swung angularly with respect to the other about the pivot established by the interengagement of the parts 21 and 25. Thus, these parts may be initially engaged with the axes of the two units angularly displaced and then one unit may be swung into alignment with the other to engage the locking members near the front of the units, as described below.

Again referring to Figures 5 and 6, the locking member 22 adjacent the front end of the top of the lower shell is struck upwardly from the top 10 and is provided with a central groove 37 which terminates just short of the free edge of the member; the metal of the top is slit as at 38 to permit displacement of the member 22 from the plane of the top and to provide openings to receive the tongue 27 of the lower unit. It will be noted that the slit 38 extends toward the front of the cabinet on both sides of the locking member 22 as at 39 which, as will appear below, permits interlocking of two units to take place by lateral movement of the forward part of one section with respect to the forward part of the other unit.

To receive the locking member 22 of a lower shell, the bottom 12 (see Figures 3 and 4) of each shell is provided with the recessed portion 26, the metal of the bottom being slit as at 40 leaving the forwardly projecting tongue 27 disposed substantially in the plane of the bottom. The tongue 27 is provided with a central raised por-

tion 41 having a smaller depression 42 therein. The portion 26, which extends on either side of the tongue 27, receives the tongue 22 of the top of a lower shell when the parts are assembled with the interlocking parts at the rear or the shells in engagement with each other but with the axes of the shells angularly displaced as shown in broken lines in Figure 7. Then, when the upper shell is rotated with respect to the lower shell about the pivot established by the interengagement of the interlocking parts 21 and 25, the parts take the position shown in full lines in Figure 7 and in Figure 8. There it will be seen that the rearwardly projecting locking member 22 of the top 10 of the lower shell is disposed over the projecting tongue 27 of the bottom 12 of the upper shell with the bottom of the groove 37 engaging within and making a snap fit with the groove 42 in the raised portion 41 of the tongue 27.

When the parts are so assembled, the disposition of the tongue 27 beneath the locking member 22 prevents relative vertical movement of the parts. The snap fit between the bottom of the groove 37 and the top of the groove 42 prevents accidental lateral displacement of the parts with respect to each other while permitting ready detachment when desired. The engagement of the end portion 44 of the tongue 22 with the sloping shoulder 45 at the end of the groove 42 prevents relative movement of the upper section in a forwardly direction with respect to the lower section. Inasmuch as the locking parts at the rear of the filing cabinet prevent rearward movement of the upper section with respect to the lower section, it will be seen that the assembled units are securely locked against longitudinal movement in either direction and against vertical movement at either end of the assembly. Also, the parts are firmly held against accidental lateral displacement although the sections may be readily dis-assembled when desired. All this is accomplished without requiring any additional separately formed parts and without requiring any movable parts or additional metal in the shells. All of the interlocking parts are fixed with respect to the shell and hence may be formed rapidly and economically from the metal of the tops and bottoms of the shells by simple stamping operations, the interlocking parts being integral with the shells themselves. While I prefer to arrange the interlocking parts as shown with the pivotal interlock at the rear of the units, the arrangement may be reversed if desired and the units arranged with interlocking parts 21 and 25 near the front of the units and the parts 22 and 27 at the rear.

Those skilled in the art will appreciate that various changes and modifications may be made in my invention without departing from the spirit and scope thereof. Accordingly, it is to be understood that my patent is not limited to the preferred form of the invention described herein or in any manner other than by the appended claims.

65 I claim:

1. A pair of filing units or the like adapted to be locked together in superposed relationship, the top wall of the lower unit and the bottom wall of the upper unit having interengaging parts 70 near one end thereof adapted to prevent that end of the upper unit from being lifted from the lower unit and to prevent the upper unit from being moved in one direction with respect to the lower unit, and said units having interengaging parts 75 adjacent the other end thereof, one of said parts

carried by the top wall of the lower unit having open sides and having a portion thereof spaced above the plane of said top wall and overlying the other of said parts carried by the bottom wall of the upper unit, said parts being engageable by lateral movement of the adjacent portion of one unit with respect to the other, said other of said parts occupying the space between said one part and the plane of said top wall whereby to prevent the adjacent end of the upper unit from being lifted from the lower unit and to prevent the upper unit from being moved in the opposite direction with respect to the lower unit.

2. A pair of filing units or the like adapted to be locked together in superposed relationship, the top wall of the lower unit having a forwardly facing recess and the bottom wall of the upper unit having a rearwardly extending tongue near the rear thereof adapted to engage within said recess to prevent the rear of the upper unit from being lifted from the lower unit and to prevent the upper unit from being moved rearwardly with respect to the lower unit, and said units having interengaging parts adjacent the front thereof, one of said parts carried by the top wall of the lower unit having open sides and having a portion thereof spaced above the plane of said top wall and overlying the other of said parts carried by the bottom wall of the upper unit, said parts being engageable by lateral movement of the front portion of one unit with respect to the other, said other of said parts occupying the space between said one part and the plane of said top wall whereby to prevent the front of the upper unit from being lifted from the lower unit and to prevent the upper unit from being moved forwardly with respect to the lower unit.

3. A pair of filing units or the like adapted to be locked together with adjacent walls of the units in face-to-face relationship, one wall of one unit having a forwardly facing recess and the adjacent wall of the other unit having a rearwardly extending tongue near one end thereof adapted to engage within said recess to prevent the units from being moved apart bodily and to prevent one unit from being moved in one direction with respect to the other unit, and said walls having interengaging parts adjacent the other ends of said units, one of said parts carried by the top wall of the lower unit extending rearwardly therefrom and having open sides and having a portion thereof spaced above the plane of said top wall and overlying the other of said parts carried by the bottom wall of the upper unit, said parts being engageable by lateral movement of the adjacent portion of one unit with respect to the other, said other of said parts extending forwardly from the bottom wall of the upper unit and occupying the space between said one part and the plane of said top wall whereby to prevent the units from being moved apart bodily and to prevent the one unit from being moved in the opposite direction with respect to the other unit.

4. A pair of filing units or the like adapted to be locked together with adjacent walls of the units in face-to-face relationship, one wall of one unit having a forwardly facing recess and the adjacent wall of the other unit having a rearwardly extending tongue near one end thereof adapted to engage within said recess to prevent one unit from being moved in one direction with respect to the other unit, and said walls having interengaging parts adjacent the other ends of said units, one of said parts carried by

the top wall of the lower unit extending rearwardly therefrom and having open sides and having a portion thereof spaced above the plane of said top wall and overlying the other of said parts carried by the bottom wall of the upper unit, said parts being engageable by lateral movement of the adjacent portion of one unit with respect to the other, said other of said parts extending forwardly from the bottom wall of the upper unit and occupying the space between said one part and the plane of said top wall whereby to prevent the one unit from being moved in the opposite direction with respect to the other unit.

5. A pair of filing units or the like adapted to be locked together in superposed relationship, the top wall of the lower unit having an upwardly raised portion opening forwardly and the bottom wall of the upper unit having a rearwardly extending tongue near the rear thereof adapted to engage within said raised portion to prevent the rear of the upper unit from being lifted from the lower unit and to prevent the upper unit from being moved rearwardly with respect to the lower unit, the top wall of the lower unit having a raised rearwardly facing locking member adjacent the front thereof and the bottom wall of the upper unit having a forwardly facing tongue engageable with said locking member by lateral movement of the front portion of one unit with respect to the other, the engagement of said parts being adapted to prevent the front of the upper unit from being lifted from the lower unit and to prevent the upper unit from being moved forwardly with respect to the lower unit.

6. The combination defined in claim 5 wherein the top and bottom walls of the units are formed of sheet metal and wherein the interengaging parts are integral with said walls.

7. A pair of filing units or the like adapted to be locked together in superposed relation each having a top wall and a bottom wall, the top wall of the lower unit and the bottom wall of the upper unit having overlapping longitudinally abutting interengaging parts near the rear thereof adapted to prevent the rear of the upper unit from being lifted from the lower unit and to prevent the upper unit from being moved rearwardly with respect to the lower unit, one of said walls having a raised rearwardly facing locking member adjacent the front thereof and the other of said walls having a forwardly facing tongue integral therewith, said locking member overlapping and longitudinally abutting said tongue whereby to prevent the front of the upper unit from being moved forwardly with respect to the lower unit, and said forwardly facing tongue being laterally engageable with said locking member by lateral movement of the front portion of one unit with respect to the other.

8. The combination of claim 7 in which said one of said walls is the top wall of the lower unit, and said other of said walls is the bottom wall of the upper unit.

9. A pair of filing units or the like adapted to be locked together in superposed relationship, the top wall of the lower unit and the bottom wall of the upper unit having interengaging parts near the rear thereof adapted to prevent the rear of the upper unit from being lifted from the lower unit and to prevent the upper unit from being moved rearwardly with respect to the lower unit, the top wall of the lower unit having a raised rearwardly facing locking member adjacent the front thereof and the bottom wall of the upper unit having a forwardly facing tongue engage-

able with said locking member by lateral movement of the front portion of one unit with respect to the other, the engagement of said parts being adapted to prevent the front of the upper unit from being lifted from the lower unit and to prevent the upper unit from being moved forwardly with respect to the lower unit, said tongue and locking member having interengaging grooves extending longitudinally of the units adapted to prevent accidental lateral displacement thereof.

10. A pair of filing units or the like adapted to be locked together in superposed relationship, the top wall of the lower unit and the bottom wall of the upper unit having interengaging parts near the rear thereof adapted to prevent the rear of the upper unit from being lifted from the lower unit and to prevent the upper unit from being moved rearwardly with respect to the lower unit, the top wall of the lower unit having a raised rearwardly facing locking member adjacent the front thereof and the bottom wall of the upper unit having a forwardly facing tongue engageable with said locking member by lateral movement of the front portion of one unit with respect to the other, the engagement of said parts being adapted to prevent the front of the upper unit from being lifted from the lower unit and to prevent the upper unit from being moved forwardly with respect to the lower unit, said tongue and locking member having interengaging grooves extending longitudinally of the units adapted to prevent accidental lateral displacement thereof, the bottom wall of the upper unit being recessed on either side of said tongue to receive said locking member to permit the upper unit to be disposed on the lower unit with their adjacent walls in contact with said locking member received in the recessed portion of the bottom wall and then to be moved laterally with respect to the lower unit to bring said tongue into engagement with said locking member.

11. Means for interlocking a pair of filing cabinets or the like, comprising first means fixed adjacent one end of the top wall of one unit and second means fixed adjacent the same end of the bottom wall of another unit, said first means overlapping said second means, said first and second means disposed to longitudinally abut and engage each other to prevent relative longitudinal movement of the units in one direction, and laterally engageable overlapping longitudinally abutting interlocking means fixed adjacent the

other ends of the units adapted when interlocked to prevent relative longitudinal movement of the units in the opposite direction and engageable by relative rotational movement between the units

5 substantially about the pivot established by engagement of said first and second means.

12. The interlocking means of claim 11 in which said one end is the rear end of said units and said other ends are the front ends of the units.

10. 13. A pair of filing units disposed in stacked relation each having a top wall and a bottom wall, the top wall of the lower unit and the bottom wall of the upper unit each having interengaging

15 parts near the rear and near the front thereof, said rear parts comprising a slot in one of said walls, and an upwardly raised forwardly projecting rear locking member extending over said slot and having shoulders, a tongue struck from the

20 other of said walls and having shoulders and extending rearwardly under said rear locking member whereby to prevent relative vertical movement between said filing units, said shoulders of said rear tongue and said rear locking member

25 engaging to resist rearward movement of said upper unit relative to said lower unit, said front parts comprising a slot in said one of said walls, an upwardly raised rearwardly projecting locking member integral with said one of said walls

30 and extending over said slot and having an end portion, a tongue struck from said other of said walls and having shoulders and extending forwardly under said front locking member whereby to resist relative vertical movement between said

35 upper and lower filing units, said shoulders of said front tongue engaging the end portion of said front locking member to resist rearward movement of said upper unit relative to said lower unit, and laterally engageable locking means

40 carried by said front locking member and said front tongue.
